ATTORNEY.

UNITED STATES PATENT OFFICE.

TRUMAN MABBETT, JR., OF BEIDEMAN STATION, NEW JERSEY.

DESIGN FOR JUG.

SPECIFICATION forming part of Design No. 12,183, dated March 8, 1881.

Application filed December 11, 1880. Term of patent 7 years.

To all whom it may concern:

Be it known that I, TRUMAN MABBETT, Jr., a citizen of the United States, residing at Beideman Station, in the county of Camden, State of New Jersey, have invented and produced a new and original Design for a Jug, of which the following is a specification, reference being had to the accompanying drawing, forming part thereof.

10 The figure is a perspective view of my newly-designed jug.

A represents the body of the jug; B, the handle; C, the spout, and D the outlet or faucet attachment.

15 The body A is of the form of an apple, having its stem tubular to constitute the spout C, and the handle B of the form of a bent twig

projecting from and laterally continuous of the stem and joined to the body, as at a. The end of the twig is bifurcated and formed with 20 leaves b, which join the body, the bifurcation and leaves not being essential features.

I claim—

The design for a jug the body A whereof is of the form of an apple, with a spout, C, of 25 the form of the apple-stem, and a handle, B, of the form of a twig, which extends laterally from the apple-stem and joins the body, as shown and described.

TRUMAN MABBETT, JR.
